LOCK

Gerald E. Redenbaugh, Detroit, Mich., assignor to
 Chrysler Corporation, Highland Park, Mich., a
 corporation of Delaware

Application July 25, 1945, Serial No. 606,894

11 Claims. (Cl. 292—169)

1

This invention relates to a holding and locking device. More specifically it relates to a door lock for an automotive vehicle.

Locks are known that involve locking by displacement of an intermediate member to an inoperative position in which it does not transmit movement of a handle control member to a door bolt and also involve prevention of accidental lock-out by the return of the intermediate member to operative position through retraction of the bolt caused by closing of the door. I have invented a construction that incorporates the intermediate member as described above and prevention of accidental lock-out to a door lock of the type having a bolt retractible only on opening and not on closing of the door.

An object of the present invention is to provide improvements in a door lock of the type that effects locking by shifting an intermediate member to an inoperative position and thus prevents motion of a control member from being transmitted to a door-holding means. More specifically, the lock may be of the type in which the holding means may be suitably actuated on closing of the door to prevent accidental lock-out and to permit deliberate lock-out.

A further object is to provide an improved door lock of the type that has a holding means retractible only on opening of the door and not on closing. The lock may include suitable means for preventing accidental lock-out and permitting deliberate lock-out.

Another object is to make improvements in a door lock of a kind effecting locking by shifting an intermediate member to an inoperative position and having holding means preventing accidental lock-out and permitting deliberate lock-out.

Other objects will appear from the disclosure.

In the drawings:

Fig. 1 is a view partially in section showing the novel lock of the present invention and a portion of the vehicle door in which it is mounted, the lock being in holding and non-locking position;

Fig. 2 is a similar view with the bolt of the lock in retracted position;

Fig. 3 is a similar view with the lock bolt in holding position and the lock in locking position;

Fig. 4 is a similar view with the parts shown in position for a deliberate lock-out;

Fig. 5 is an end view of the door on which the lock is mounted; and

2

Fig. 6 is a sectional view taken on the line 6—6 of Fig. 1.

The reference character 10 designates a vehicle door having a flange 11 for the lower side of a door window, not shown, and an edge flange 12. To the edge flange 12 is secured by means of screws 12^a a flange 13 of a mounting plate 14, the main body portion of which extends at right angles to the flange 13 and to the end flange 12 of the door 10. A bolt 15 is composed of a block member 16 and an elongated sheet metal member 17 attached to the block member by rivets 18. The bolt 15 is urged to the right as viewed in Fig. 1 by means of a spiral return spring 18^a secured as indicated at 18^b to the mounting plate 14 and acting against one end of the bolt block 16. The block member 16 projects through and is supported by openings in the end flange 12 of the door and the flange 13 of the mounting plate 14. An upper inclined surface 10^c on the block member 16 of the bolt is engageable with a catch 19 (see Figure 6) mounted on a pivot 20. The catch 19 is urged downwardly as viewed in Fig. 6 by a spring 21 and is positioned in a housing 22 fastened to a door pillar 23. The bolt block 16 has a lower inclined surface 24 engageable with a safety catch 25, mounted on the door pillar 23 by a pivot 26. Catch 25 is urged upwardly by a coil spring 27 and is positioned in a housing 28 attached to the door pillar 23. The sheet metal member 17 of the bolt 15 has an elongated slot 29 receiving the body of a rivet 30 attached to the mounting plate 14. The rivet 30 provides sliding support for the left end of the bolt 15. The sheet metal member 17 is maintained in spaced relation to the mounting plate 14 at its right end as viewed in Fig. 1, by the block 16 to which it is secured and at its left end by a bearing block 31 appropriately secured to the mounting plate 14. A rivet 32 on the left end of the sheet metal member 17 of the bolt 15 is received in an elongated slot 33 formed in one end of a link 34. The other end of the link 34 is suitably connected to an inside control handle 35. The left end of the member 17 is formed with a projection or shoulder 36 having inclined surfaces 37 and 38 and a vertical surface or shoulder 39. The shoulder 39 is engageable with one end of a horizontal flange 40 formed on the top and adjacent the left end of an intermediate member 41. The intermediate member 41 carries a rivet 42 received in an elongated slot 43 formed in the mounting plate 14 and has a vertical flange 44 at its right end engaged at its inner side by a spiral return spring 45 attached

as indicated at 46 to the mounting plate 14. The outer side of the flange 44 on the intermediate member 41 is engaged by a roll-back 47. The roll-back is secured to a square shaft 48 to which is also secured an outside control handle 49. The intermediate member 41 has an elongated slot 50 receiving a rivet 51 secured to a control part comprising pivoted plate 52. The pivot for the plate 52 is constituted by a rivet 53 secured to the mounting plate 14. An extension 54 is secured by rivets 55 to the pivoted plate 52 and has a flange 56 engageable with the right end of the link 34. An over-center coil spring 57 connected at one end to the pivoted plate 52 and at the other end of the mounting plate 14 tends to maintain the pivoted plate 52 either in the position of Fig. 1 or in the position of Fig. 3. An elongated slot 58 formed in the pivoted plate 52 and a rivet 59 received in the slot 58 and secured to the mounting plate 14 combine to limit the angular movement of the pivoted plate 52 about the rivet 53. A vertical rod 60 projects through a flange 61 formed on the pivoted plate 52 and by means of opposite portions 62 formed on the rod and a cotter pin 63 passing through the rod is enabled through its own vertical movement to control the position of the pivoted plate 52. The rod 60 projects through the flange 61 on the door 10 and has at its upper end a push button 64. A rod-like spring 65 is secured generally at one end by parts 66 and 67 to the pivoted plate 52 and carries at its other end a striker 68 engageable with inclined surfaces 69 and 70 formed on a projection 71 secured by screws 72 to the door pillar 23. The pivoted plate 52 has a re-entrant follower portion 73 adapted to be engaged by a cam 74 fixed to a square shaft 75 controlled by an outside key 76.

When the above described parts are in the position of Fig. 1 the door 10 is held shut, since opening of the door would involve movement of the bolt block 16 to the right, as viewed in Fig. 6 and this cannot take place because the catch 19 prevents such movement. In the position of Fig. 2 the bolt 15 is shown in retracted position, this position having been brought about by actuation of the outside control handle 49 acting through the square shaft 48 to shift the roll-back 47 in a counterclockwise direction from the position of Fig. 1. Such shifting of the roll-back produces leftward movement of the intermediate member 41, and by virtue of engagement of the flange 40 on the intermediate member with the shoulder 39 on the sheet metal member 17 of the bolt 15, the bolt 15 moves leftward to the non-holding position of Fig. 2. Although it is not shown, the bolt 15 may also be moved to the left by suitable actuation of the inside control handle 35, which brings about leftward movement of the link 34, engagement of the right end of the slot 33 with the rivet 32, and leftward movement of the bolt 15.

When the door is to be locked from the inside, downward pressure is applied against the push button 64, which is inside of the window glass, not shown, to cause downward movement of the rod 60. This brings about a small clockwise angular movement of the pivoted plate 52 about the rivet 53 from the position of Fig. 1 to that of Fig. 3. The rivet 51 on the pivoted plate 52 acts against the slot 50 in the intermediate member 41 to move the left end of the intermediate member down to the position of Fig. 3. Now if the outside control handle 49 is actuated to move the roll-back 47 in a counterclockwise direction,

the resulting leftward movement of the intermediate member 41 is without effect upon the bolt 15. This is due to the fact that the flange 40 on the intermediate member has been depressed sufficiently that it does not engage the shoulder 39 on the bolt 15, but merely slides down the inclined surface 37 to the position of Fig. 4. When the intermediate member 41 is to be returned from its inoperative position of Fig. 3 to its operative position of Fig. 1 in order that the door may be opened by actuation of the outside control handle 49, the push button 64 is grasped and the rod 60 is raised, causing return of the intermediate member 41 to the position of Fig. 1. The intermediate member 41 may also be brought to its inoperative position of Fig. 3 by means of the inside control handle 35. This handle is suitably actuated to cause a rightward movement of the link 34 resulting in engagement of the right end of the link 34 with the flange 56 on the extension piece 54 attached to the pivoted plate 52. The result is the slight clockwise movement of the pivoted plate 52 to the position of Fig. 3 and the movement of the intermediate member 41 to its inoperative position.

Let it now be assumed that the door is open and that the intermediate member 41 is in the inoperative position of Fig. 3. If then the roll-back 47 is left in the position of Fig. 3 and the door is closed, this action will cause the striker 68 to engage the inclined surface 69 on the projection 71, thereby lifting the striker. The striker acting through the rod-like spring 65 urges the pivoted plate 52 counterclockwise to the position of Fig. 1, thereby causing a turn of the intermediate member 41 to operative position. In this way accidental lockout is prevented.

If a deliberate lockout is desired, the door is opened, the intermediate member 41 is brought to the inoperative position of Fig. 3 either by actuation of the inside control handle 35 or by depression of the rod 60, and thereafter the outside control handle 49 is actuated to shift the roll-back 47 in a counterclockwise position from that of Figs. 1 and 3, all as shown in Fig. 4. Now as shown in Fig. 4 the left end of the intermediate member 41 is both depressed and shifted to the left so that it engages the point of blocking shoulder projection 36. Now when the door is closed and as a result the striker 68 is raised as it passes over the inclined surfaces 69 and 70 the rod-like spring 65 connecting the striker and the pivoted plate 52 flexes and permits the pivoted plate to remain as shown in Fig. 4, the engagement of the intermediate member 41 with the end of the projection 36 maintaining the pivoted plate 52 in the position of Fig. 4 in spite of the upward urging of the pivoted plate by the leverage applied to spring 65 through striker 68. After the door has thus been shut, the parts assume the locking position of Fig. 3. Unlocking may be effected by lifting of the vertical rod 60. This lifting of rod 60 will, of course, have to be accomplished by someone inside the car for it is assumed that the push button 64 is positioned inside of a closed door window.

The door may also be unlocked by actuation of the key 76 acting upon the square shaft 75 to rotate the cam 74. The lock in which the key 76 operates is not shown in detail since it forms per se no part of the present invention. It is sufficient to state that the lock will be of the type requiring a complete revolution of the key 76 in one direction for locking before it can be withdrawn from the lock and a complete revolu-

tion in the other direction for unlocking before it can be withdrawn from the lock, with appropriate stops to limit the movement of the key in either direction after a complete revolution in that direction. For unlocking, the key 76 is given a complete revolution in the proper direction to effect a complete revolution of the shaft 75 and the cam 74 in a clockwise direction as viewed in Fig. 3. The cam 74 in its complete revolution will engage the upper side of the re-entrant follower portion 73, causing the return of the pivoted plate and the intermediate member 41 to the operative position of Fig. 1. The door may be locked by a complete revolution of the key 76 causing a complete revolution of the shaft 75 and cam 74 in a counterclockwise direction as viewed in Fig. 1. The cam 74 in its counterclockwise revolution will engage the lower side of the re-entrant follower portion 73, causing movement of the pivoted plate and the intermediate member 41 to the inoperative position of Fig. 3.

If the door is closed and locked either by the push button 64 or by the inside control handle 35 or by the outside key 76, unlocking of the door may, of course, be effected by any one of the last three mentioned means. If now the inside control handle 35 is appropriately actuated the link 34 will be moved to the left, carrying with it the bolt 15 to non-holding position. The door may now be opened and as this takes place the striker 68 moves to the right as viewed in Fig. 6, up the inclined surface 76. This upward movement of the striker causes the rod-like spring 65 to urge the pivoted plate 52 and the intermediate member 41 back to the operative position of Fig. 1.

I claim:

1. A control mechanism for a retractile bolt for a vehicle door adapted for use with a door pillar keeper of the type permitting shutting of the door without retraction of the bolt, said control mechanism comprising a handle control member, an intermediate member having an operative position for transmitting movement of the handle control member to the bolt for retraction and an inoperative position preventing transmission of such movement, a part pivoted on the door and connected to the intermediate member so as to have one position producing an inoperative position of the intermediate member and another position producing an operative position of the intermediate member, a projection mounted in the door pillar, a striker resiliently connected to the pivoted part and engageable with the projection upon opening and closing of the door so as to move the part from the said other position to the said one position for restoring the intermediate member to an operative position, the intermediate member being shiftable from its inoperative position to a blocking position by actuation of the handle control member so as to engage both the bolt and the pivoted part and thereby to prevent movement of the pivoted part from the said other position to the said one position in spite of engagement of the striker with the projection upon opening or closing of the door, the resilient connection of the striker with the pivoted part permitting this to take place.

2. A control mechanism for a retractile bolt for a vehicle door adapted for use with a door pillar keeper of the type permitting shutting of the door without retraction of the bolt, said control mechanism comprising a control member operable from the outside of the vehicle door, an

intermediate member acting in a first position between the control member and the bolt to enable actuation of the control member to effect retraction of the bolt for opening the door, a part controllable from the inside of the vehicle door and connected with the intermediate member so as to have a first position causing the intermediate member to occupy its said first position and a second position causing the intermediate member to occupy a second position enabling actuation of the control member without retraction of the bolt, an anti-lockout element resiliently connected with the part and engageable with means on the door pillar upon opening and shutting of the door so as to move the part from its second position to the first position, the control member being actuatable to shift the intermediate member to a third position involving engagement with both the bolt and the part for preventing return of the part and the intermediate member to their first positions in spite of engagement of the anti-lockout element with the means in the door pillar upon closing of the door, the resilient connection of the anti-lockout element with the part making possible the retention of the part in its second position in spite of closing of the vehicle door.

3. A control mechanism for a retractile bolt for one of a pair of cooperating vehicle body and door members adapted for use with a keeper in the other of the vehicle body and door members of the type permitting shutting of the door member without retraction of the bolt, said control mechanism comprising operating and blocking shoulders carried by the bolt, a control member operable by an outside control, an intermediate member having an operative position in which it is engageable with the first-named shoulder on the bolt whereby the control member acts against the intermediate member to cause the same to retract the bolt, means manually operable either by an outside key-operated means or an inside control for shifting the intermediate member to an inoperative position removed from engagement with the first shoulder on the bolt whereby the control member is prevented from acting through the intermediate member to retract the bolt and whereby the control member is effective to act against the intermediate member to cause the same to engage against the said blocking shoulder and to be enforcedly retained thereby out of said operative position, and means including a part operatively removed from influence of movement of said bolt responsive to shutting of the door member for normally thereupon moving and automatically urging the intermediate member from inoperative position to operative position, said part having a spring portion resiliently operative between the door and body members upon shutting of the door to flex without transmitting said motion to the intermediate member under condition of enforced retention of said intermediate member out of said operative position by said control member.

4. A control mechanism for a retractile bolt for a vehicle door adapted for use with a vehicle body mounted keeper of the type permitting shutting of the door without retraction of the bolt, said control mechanism comprising a handle controlled member operable from outside the vehicle, means for selectively causing operation of the handle controlled member to be effective or ineffective to retract the bolt including a part pivotally supported to swing on the door through a path of movement between re-

pective positions for selectively causing the operation of the handle controlled member to be effective or ineffective to retract the bolt, and means acting in response to shutting of the door to swing said part in a direction from one to another of said positions including paired elements adapted for respective mounting one on said first mentioned means and the other on said body to engage upon shutting of the door so as to move said one element for swinging said part in said direction from one position to the other, and means mounting said elements on said first mentioned means and body in disassociation to said bolt and keeper for independent engagement and response to shutting of the door.

5. A control mechanism for a retractile bolt for a vehicle door adapted for use with a vehicle body mounted keeper of the type permitting shutting of the door without retraction of the bolt, said control mechanism comprising a handle controlled member operable from outside the vehicle, means for selectively causing operation of the handle controlled member to be effective or ineffective to retract the bolt including a part pivotally supported to swing on the door through a path of movement between respective positions for selectively causing the operation of the handle controlled member to be effective or ineffective to retract the bolt, and means acting in response to shutting of the door to swing said part in a direction from one to the other of said positions including engageable elements one associated with said first mentioned means and the other associated with said body to engage upon shutting of the door so as to move said one element for swinging said part in said direction from one position to the other, and means for mounting and positioning one of said engageable elements on said first mentioned means and the other on said body respectively in disassociation to said bolt and keeper for independent engagement and response to shutting of the door, at least one of said mounting and positioning means comprising a yieldable member.

6. A control mechanism for a retractile bolt for a vehicle door adapted for use with a vehicle body mounted keeper of the type permitting shutting of the door without retraction of the bolt, said control mechanism comprising a handle controlled member operable from outside the vehicle, means for selectively causing operation of the handle controlled member to be effective or ineffective to retract the bolt including a part pivotally supported to swing on the door through a path of movement between respective positions for selectively causing the operation of the handle controlled member to be effective or ineffective to retract the bolt, said part being when in ineffective position displaceable at least partially out of said path of movement by operation of said handle controlled member and having associated therewith means for simultaneously blocking shifting movement thereof into said effective position, and mechanism acting in response to shutting of the door for swinging said part in a direction from ineffective to effective position including engageable abutments one associated with the first-said means and another associated with said body to engage upon shutting of the door so as to move said one element for swinging said part in said direction from said ineffective to effective position and including means for mounting and positioning said one engageable abutment on the first-said means and said other engageable abutment on the body

respectively in disassociation to said bolt and keeper for independent engagement and response to shutting of the door, at least one of said mounting and positioning means comprising a yieldable member for yieldably compensating for engagement of said abutments due to shutting of the door during circumstance of displacement by said handle controlled member of said part to block its shifting movement into said effective position.

7. A control mechanism for a retractile door bolt adapted for use with a door pillar keeper permitting closing of the door without retraction of the bolt including a handle operated rollback, means interconnecting the rollback and bolt including an element connectable with and disconnectable from the bolt, plate means shiftably supporting said element and adapted to move it into connected and disconnected positions with respect to the bolt, and means coacting with the plate means operable independently of said bolt and actuatable engageable upon closing of the door with means on the door pillar for shifting said plate means and said element for effecting connection between said element and bolt upon door closing movement while the bolt remains in extended position.

8. A control mechanism for a retractile door bolt adapted for use with a keeper permitting closing of the door without retraction of the bolt including a handle operated rollback, a support plate shiftably mounted on the door structure and having associated therewith overcenter means cooperating with the support plate in response to partial shift thereof to complete the shift, means for operatively interconnecting the rollback and bolt for retracting the bolt including an element shiftable by the support plate for movement into and out of retracting engagement with said bolt, said element being shiftable to a third position by action of the rollback for holding the element and said support plate against movement into said bolt retracting position, and yieldable means carried by the support plate for initiating movement thereof and cooperating with said overcenter means to shift the support plate and bring said element into retracting engagement with said bolt upon door closing movement, said last mentioned means being adapted to yield during door closing movement when said element is held in said third position.

9. A control mechanism for a retractile door bolt adapted for use with a keeper permitting closing of the door without retraction of the bolt including a handle operated rollback, a support plate shiftably mounted on the door structure and having associated therewith overcenter means cooperating with the support plate in response to partial shift thereof to complete the shift, shoulders including a holding shoulder and a retracting shoulder for retracting the bolt, at least said retracting shoulder being carried by the bolt, means for operatively interconnecting the rollback and bolt for retracting the bolt including an element shiftable by the support plate for movement into and out of retracting engagement with said bolt retracting shoulder, said element being shiftable by said rollback to a third position for engagement with said holding shoulder for holding said element and said support plate against movement into said bolt retracting position, and yieldable means carried by the support plate for initiating partial shift thereof and cooperating with said overcenter means to complete the shift of the support plate and bring said element into

retracting engagement with said bolt retracting shoulder upon door closing movement, said last mentioned means being adapted to yield during door closing movement when said element is held in said third position.

10. A control mechanism for a retractile door bolt adapted for use with a door pillar keeper permitting closing of the door without retraction of the bolt including a handle operated rollback, a support plate shiftably mounted on the door structure so as to be operable either by an outside key-operated means or an inside handle control, means for operatively interconnecting the rollback and bolt for retracting the bolt including an element shiftable by the support plate for movement into and out of retracting engagement with said bolt, said element being shiftable to a third position by action of said rollback for holding said element and said support plate against movement into said bolt retracting position, and yieldable means carried by the support plate for shifting it to bring said element into retracting engagement with said bolt upon door closing movement, said last mentioned means being adapted to yield during door closing movement when said element is held in said third position and having an abutment element engageable with means on the door pillar upon closing of the door.

11. A control mechanism for a retractile door bolt adapted for use with a door pillar keeper permitting closing of the door without retraction of the bolt including a handle operated rollback, a support plate shiftably mounted on the door

5 structure, means for operatively interconnecting the rollback and bolt for retracting the bolt including an element shiftable by the support plate for movement into and out of retracting engagement with said bolt, said element being shiftable to a third position by action of said rollback for holding said element and said support plate against movement into said bolt retracting position, and means for shifting the support plate to bring said element into retracting engagement with said bolt upon door closing movement, said last mentioned means being restricted in operation during door closing movement when said element is held in said third position and comprising a member affixed to said support plate and provided with a resilient portion and a striker portion carried by the resilient portion adapted to engage means on the door pillar upon closing of the door for thereby yieldably urging shift of said support plate.
